UNITED STATES PATENT OFFICE.

WALTER E. BARNES, OF BRIDGEPORT, CONNECTICUT, ASSIGNOR TO UNION SPECIAL
MACHINE COMPANY, OF CHICAGO, ILLINOIS, A CORPORATION OF ILLINOIS.

GARMENT.

1,108,668.

Specification of Letters Patent. Patented Aug. 25, 1914.

Application filed January 23, 1905. Serial No. 242,352.

To all whom it may concern:

Be it known that I, WALTER E. BARNES, a citizen of the United States, residing at Bridgeport, in the county of Fairfield, State 5 of Connecticut, have invented certain new and useful Improvements in Garments, of which the following is a description, reference being had to the accompanying drawing, and to the letters and figures of reference marked thereon.

My invention relates to an improvement in the manufacture of garments, and particularly to a seam for use in the manufacture of ladies' shirt waists; night gowns, 15 eider-down sacks, kimonos, wrappers and different garments of this nature, in sewing and binding the sleeves onto the body portion, or in sewing and binding the shoulders or the sides thereof. Heretofore in the 20 manufacture of such garments a series of operations has been necessary to accomplish the work of taping the seam, and when the edges of two pieces of fabric have been bound and sewed, an objectionable and 25 bulky and on thin goods an unsightly, seam has resulted.

It is the object of my invention to provide a simple, cheap, strong and ornamental seam for the purpose mentioned, and the 30 invention, therefore, consists in the matters hereinafter described and referred to in the appended claim.

The invention is illustrated in the accompanying drawings, in which—

35 Figure 1 is an exaggerated view of a portion of a garment showing the shoulder seam and the sleeve united to the garment, said garment being turned wrong side out, Fig. 2 is a similar view on a smaller scale, 40 illustrating some of the garment, Fig. 3 is a cross section of the seam, Fig. 4 is a top perspective view of the same.

In these drawings, A represents the material of which the sleeve of a lady's shirt 45 waist is composed, it being rufled as shown at intervals, in the well known manner to make it fit the sleeve opening.

B represents the body of the shirt waist. The adjacent raw edges of the material are 50 superposed and overseamed by stitches having threads a, covering the edges above and below, and a tape C, herein shown of greater width than the width of the overseam is

laid upon the material, and a row of loops b passed through the same, and the two 55 thicknesses of material, leaving a portion of the tape exposed beyond the line of stitching, to give a neat appearance and strength and suitable bight in the tape for said stitches, the overedge threads lying above 60 and below the fabrics across and around the edge.

It will be noted that the loops b pass through the superposed parts and terminate at the upper and lower faces of the parts. 65 By this construction, these loops b of needle thread will operate to firmly secure the two superposed parts together, while the loops running to the edge of the fabric will cover the edge of the fabric and bind the tape 70 about the edge of the fabric.

I have provided a seam which may be used for connecting various parts of a garment, and the raw edges will be completely covered and the parts firmly secured together.

Having thus described my invention, what I claim as new and desire to secure by Letters Patent, is:—

A garment comprising two or more parts, 80 the edge of one of the parts being superimposed upon and coinciding with the edge of the other part, a tape upon the outer face and adjacent the edge of one of said parts, a securing thread extending along the face 85 of one of said parts and having loops extending through the two parts and the tape at a distance from the edge of the united parts, said loops terminating substantially at the outer face of the tape, a second thread 90 having loops passing through the loops in the first named thread and locking the same, the loops in the second thread being extended to the edge of the united parts, a third thread having loops interlocking the 95 loops in the second thread, the loops of the third thread lying on the opposite face of the united parts and being locked by the loops formed in the first named thread.

In testimony whereof I affix my signature, 100 in presence of two witnesses.

WALTER E. BARNES.
